UNITED STATES PATENT OFFICE.

EDWIN F. COBB, OF DENVER, COLORADO, ASSIGNOR OF FORTY-FIVE ONE-HUNDREDTHS
TO WALTER EAST, TRUSTEE, OF DENVER, COLORADO.

PACKAGE-TIE.

1,271,436.

Specification of Letters Patent.

Patented July 2, 1918.

Application filed July 13, 1914. Serial No. 850,729.

To all whom it may concern:

Be it known that I, EDWIN F. COBB, a citizen of the United States, residing at Denver, in the city and county of Denver 5 and State of Colorado, have invented certain new and useful Improvements in Package-Ties; and I do hereby declare the following to be a full, clear, and exact description of the invention, such as will enable 10 others skilled in the art to which it appertains to make and use the same.

My invention relates to improvements in tying devices for packages and resides in the provision of a simple, inexpensive and 15 effective device by means of which a cord may be securely held in proper position upon a package, bundle or the like without necessitating knotting thereof.

Another object is to provide a device of 20 the character described that may be readily stamped out of a single blank of metal, will permit of the use of a cord a number of times and which is inexpensive to manufacture.

25 The above and additional objects are accomplished by such means as are illustrated in the accompanying drawings, described in the following specification and then more particularly pointed out as claimed.

30 With reference to the drawings, wherein I have illustrated the preferred embodiment of my invention as it is reduced to practice, and throughout the several views of which similar reference numerals designate corre-

35 sponding parts.

Figure 1 is a top plan view of a package or bundle showing my device in position thereon,

Fig. 2 is a side elevation of my improved 40 package tie, and

Fig. 3 is an end elevation.

Referring to the drawings by characters of reference, 1 designates as an entirety the body portion of my package tie which consists of an elongated shank that is curved 45 at one end and provided with a T-shaped head 2 and is reduced at the point of its formation with said head so that a tie cord 3 may be looped or suitably secured to the shank 1 about the head 2 as at 4. The body portion 1 is bowed intermediate its ends and formed preferably of some suitable 50 spring metal.

The end of the body portion 1 farthest 55 removed from the head 2 is bent back to

provide an overlying or hook portion 5 that is parallel to the body portion approximately and one side edge of the hook portion 5 lies flush with the adjacent side edge of the shank 1 and the opposite edge of the hook portion 5 has integral connection with a lateral extension 6, which extends beyond the adjacent side edge of the shank of the body 1. The point of connection between the extension 6 and the hook portion 5 is 60 disposed inwardly of the free and connected ends of the hook portion, as shown in Fig. 1 of the drawing. A tongue 7 is disposed in spaced relation with the inner edge of the hook 5 and is curved upwardly, as 65 shown in Fig. 2, and is carried by the adjacent end of the extension 6. The opposite end of the extension 6 is provided with a tongue 8, which is disposed beyond the point of juncture between the hook and the shank 70 of the body 1 and spaced therefrom, as shown in Fig. 1, and is terminally curved upwardly. The tongue or extension 7 is disposed over the central part of the body plate 1 and in being turned up enables the 75 close positioning thereof relative to the body portion to insure a clamping action and at the same time the ready insertion of the cord between itself and the body plate. The overlying portion 5 is arranged very 80 close to the body plate 1 so that the cord 3 will be clamped between the portion 5 and body plate 1 as will be later more fully described.

In operation one end of the cord is 85 secured to the T-shaped head 2 of the tie and the tie is placed upon the package or bundle and held with the left hand while the cord is wound once about the package or bundle parallel with the tie and brought under the 90 portion 5 and then at right angles to the first winding as indicated by the arrow *a* and around the package or bundle and again brought beneath the overlying portion 5 as indicated by the arrow *b*, so that a 95 binding of the cord is provided. The cord is then passed beneath the lateral extension 6 to the slot provided between the tongue 7 and portion 5, then over the top of the portion 5 and again between the extension 6 100 and body plate 1 a number of times to bind the cord. The recesses between the tongues 7 and 8 and the hook 5 prevent that portion of the cord which is wrapped around the extension 6 from shifting laterally in 105 110

either direction. The spring action of the device assists in securing the cord in position. It will be readily seen that I have provided a simple, inexpensive and effective device that may be operated in an expeditious manner to securely hold the cord in position.

In practice, I have found that the form of my invention, illustrated in the drawings and referred to in the above description, as 10 the preferred embodiment, is the most efficient and practical; yet realizing that the conditions concurrent with the adoption of my device will necessarily vary, I desire to emphasize the fact that various minor 15 changes in details of construction, proportion and arrangement of parts may be resorted to, when required, without sacrificing any of the advantages of my invention, as set forth.

20 What is claimed is:—

A package tie comprising an elongated

body plate having one end thereof bent back upon itself to provide a hook portion overlying the plate, the opposite end of the plate being provided with a T-shaped head, said 25 hook engaging portion having an enlarged lateral extension extending beyond one of the longitudinal side edges of the plate, a retaining tongue formed on the forward end of said extension and extending toward 30 the opposite longitudinal edge of the body plate and lying parallel with the hook portion, and a second retaining tongue formed on the rear edge of the extension and extending rearwardly therefrom, as and for 35 the purpose specified.

In testimony whereof I affix my signature in presence of two witnesses.

EDWIN F. COBB.
